ATTORNEY.

UNITED STATES PATENT OFFICE

EDWARD F. TANNEWITZ, OF DETROIT, MICHIGAN, ASSIGNOR TO DETROIT CORD MANUFACTURING COMPANY, OF DETROIT, MICHIGAN, A CORPORATION OF MICHIGAN

WINDOW MOUNTING

Application filed June 27, 1928. Serial No. 288,580.

My invention relates to window mounting, especially for use in automobiles, and an object of my improvements is to more completely adapt the device shown in the patent granted to me May 22, 1928, No. 1,670,321, to irregular constructions.

I secure this object in the apparatus shown in the accompanying drawings, in which:

Figure 1 is a cross-section on the line I—I, 10 Figure 3.

Figure 2 is a cross-section on the line II—II, Figure 3.

Figure 3 is an elevation, partly in section on the line III—III, of Figure 2.

15 Figure 4 is a perspective view of a portion of the channel strip.

Figure 5 is a perspective view, similar to Figure 4, showing a modified construction.

20 2 is the window casing and 3 is a groove, or channel therein in which the glass travels.

25 4 is the channel strip having flanges 6—6 extending outward from the web, which web fits against the bottom of the groove 3, as shown and as shown and described in said patent.

I have found that due to a variety of casual causes the width of the groove 3, or of the channel strip 4, may vary, which is apt to impair the closeness and accuracy of the 30 fit of the assembled parts, and an object of my invention is to obviate this difficulty. To this end I form an auxiliary thin, flexible flange, or leaf, 5, that is preferably integral with the base of the strip 4 and extends 35 along and upward, diverging slightly outward from the outer face of one of the flanges 6.

If desired, a strip, or leaf, 5, may extend 40 outward upon both sides of the channel strip 4 along the outer surfaces of the flanges 6—6, as shown in Figure 5.

In Figure 3 the groove 3—3 is indicated as broadening outward slightly at 3a—3a 45 and the channel strip is indicated as of contracted width at 4a. In each of these cases the flexible strip 5 will produce a close fit, as indicated, notwithstanding the variation in width of the groove or channel strip.

50 The channel strip is usually made of rub-

ber or felt, as described in my above named patent.

What I claim is:

1. In combination with a window casing having a sash groove therein, a channel strip 55 fitting into said groove and having a flexible flange united along one edge to the lower portion of the outer side surface of said strip, extending along and upward and diverging slightly outward from an outer side 60 surface of said strip, whereby the irregularities in the width of said groove and strip are compensated for toward the outer edges of said strip.

2. In combination with a window casing 65 having a sash groove therein, a channel strip fitting into said groove and having a flexible flange united along its inner edge to the lower portion of the outer side surface of said strip, extending along and upward and diverging slightly outward from an outer side 70 surface of said strip, whereby the irregularities in the width of said groove and strip are compensated for toward the outer edges of said strip, the inner portions of said strip 75 and flange being integral.

In testimony whereof I sign this specification.

EDWARD F. TANNEWITZ.
